(57) **CLAIM**

The ornamental design for a backpack, as shown and described.

DESCRIPTION

FIG. 1 is a top perspective view of a backpack that can be used as a travel bag showing a new design;

FIG. 2 is a front side plan view of the backpack as shown in FIG. 1;

FIG. 3 is a rear side plan view of the backpack as shown in FIG. 1;

FIG. 4 is a right side plan view of the backpack as shown in FIG. 1;

FIG. 5 is a left side plan view of the backpack as shown in FIG. 1;

FIG. 6 is a top plan view of the backpack as shown in FIG. 1;

FIG. 7 is a bottom plan view of the backpack as shown in FIG. 1; and,

FIG. 8 is a rear perspective view of the backpack as shown in FIG. 1 with a rear panel being unzipped and open showing an interior of the backpack.

In the drawings the long dash-short dash broken lines are for the purpose of illustrating certain stitching. In the drawings the dash-dash broken lines are for the purpose of illustrating environment and depict portions of the design that form no part of the claimed design.

1 Claim, 8 Drawing Sheets
